DUST GOGGLE

George R. Hoffmaster, Esterly, Reading, and Jack N. Simpson, Greenfields, Reading, Pa., assignors to The Electric Storage Battery Company, Philadelphia, Pa.

Filed Nov. 22, 1965, Ser. No. 88,173

Term of patent 14 years

(Cl. D57—1)

Fig. 1.

Fig. 2.

Fig. 3.

Fig. 4.

Fig. 5.

FIG. 1 is a top perspective view of a dust goggle showing my new design;

FIG. 2 is a front view thereof; and

FIGS. 3, 4 and 5 are rear, top and side views, respectively, thereof with the headband removed, for convenience of illustration.

The characteristic features of my design for the dust goggle disclosed reside in the combination of the V-shaped rim portions at the top with the hinge portions adjacent thereto, in association with the remaining portions of the goggle as shown.

We claim:

The ornamental design for a dust goggle, substantially as shown and described.
